(57) **CLAIM**

The ornamental design for an outboard motor, as shown and described.

DESCRIPTION

FIG. 1 is a rear elevation view of an outboard motor, showing a first embodiment of our new design;

FIG. 2 is a top plan view thereof;

FIG. 3 is a front elevation view thereof;

FIG. 4 is a right, top, front perspective view thereof;

FIG. 5 is a left side elevation view thereof; and

FIG. 6 is a right side elevation view thereof.

FIG. 7 is a top plan view of an outboard motor, showing a second embodiment of our new design;

FIG. 8 is a right, top, front perspective view thereof;

FIG. 9 is a rear elevation view thereof;

FIG. 10 is a left side elevation view thereof;

FIG. 11 is a right side elevation view thereof; and,

FIG. 12 is a front elevation view thereof.

1 Claim, 12 Drawing Sheets
